UNITED STATES PATENT OFFICE.

OLIVER B. GASTON, OF ELIZABETH, NEW JERSEY.

SAFETY DEVICE FOR ELEVATORS.

SPECIFICATION forming part of Letters Patent No. 288,825, dated November 13, 1883.

Application filed August 24, 1883. (No model.)

To all whom it may concern:

Be it known that I, OLIVER B. GASTON, a citizen of the United States, residing at Elizabeth, in the county of Union and State of New Jersey, have invented a new and useful mechanical device to be attached to elevators for the purpose of protecting life by preventing the fall of the same in case the hoisting apparatus should from any cause break or give way, of which the following is a specification.

My invention is a separate arrangement hanging immediately below the elevator, but utterly independent of it in the matter of support. Separate ropes, cables, or other suitable means hold it at a fixed distance below the bottom of the elevator. This distance may be varied to suit any special case. In the drawings a distance of three inches is shown. The ropes or cables just mentioned are intended to be wound or unwound by the same power that hoists the elevator, and at such a rate as shall keep invariable the desired distance between the bottom of the elevator and my device. When the accident occurs that would have caused the elevator to fall, but which brings my contrivance into play, the elevator drops only through the distance mentioned above, and there remains firmly supported, even though the sudden shock of the drop or other cause may have occasioned the breaking or giving away of the ropes or cables that hold the device.

My invention consists of a frame or beam, of wood or iron, of a depth depending upon the material used in constructing it and the purposes for which it may be used, extending across the elevator-shaft wherever most desirable, with the ends grooved so as to straddle the vertical notch-bar and prevent it from swaying from position. Small chains or cords hold the upper or inner ends of the weights or pawls against the bottom of the elevator. Up and down the internal walls or sides of the elevator shaft or well, at the proper places in the corners or centers, notched pieces or castings of iron are continuously secured. Into these notches the lower ends of the drop or catch weights or pawls drop (when the elevator falls) by their own weight.

In the accompanying drawings, Figure 1 gives a view of the relative positions of the elevator and safety device. Fig. 1 represents

the safety device as hanging below the elevator E, suspended by rods, ropes, or cables, as may be most convenient, which pass through or outside of the elevator up to the top of the shaft. The pawls A are attached to the cross-bars B by pins S, upon which they move by their own gravity, and drop into the mortises or pockets F at the same time they catch into the notches N. The pawls A are held up to the elevator by the chains C, which hold them clear of the notch-bars N.

The operation is as follows: When from any cause the elevator falls, the pawls are released and drop instantly into the notches N, resting both upon the notches and pockets F in the cross-bar B, thus forming a continuous support across the entire shaft or well.

Fig. 2 is a top view of the safety device.

In Fig. 3 the arrangement of the safety device with respect to the elevator is the same as in Fig. 1, and moves and operates the same. The weight-bolts G are attached to or suspended under the elevator with small chains, the same as in Fig. 1, and also move by their own gravity. The operation of Fig. 3 is the same as Fig. 1, with exception of weight-bolts G in the place of pawls A.

What I claim is—

1. The pawls A, in form as shown in drawings, in combination with the cross-bar B, and in their location with respect to the elevator, for the purposes set forth, substantially as described.

2. The four pawls A, acting by their own gravitation, two of which may be suspended on pins, as in Fig. 1, to the cross-bar B, and two hung in slots in cross-bar B and held in position by small chains C, attached to the elevator, separately or together, as shown.

3. The pawls A, as shown in Fig. 1, arranged so as to drop by their own gravitation in the pockets or recesses in the cross-bar B, which, when dropped, form a perfect bridge or support across the entire shaft, from notch-bar to notch-bar, by a combination of two appliances which act independent of the elevator, as and for the purpose set forth.

OLIVER B. GASTON.
